(57) **CLAIM**

The ornamental design for a computer, as shown and described.

DESCRIPTION

FIG. 1 is a front right perspective view of a computer showing our new design;

FIG. 2 is a back left perspective view thereof;

FIG. 3 is a front view thereof;

FIG. 4 is a back view thereof;

FIG. 5 is a top view thereof;

FIG. 6 is a bottom view thereof;

FIG. 7 is a right view thereof; and,

FIG. 8 is a left view thereof.

The broken lines in FIGS. 1 and 7 depict portions of the computer that form no part of the claimed design.

1 Claim, 6 Drawing Sheets
